ATTORNEY

UNITED STATES PATENT OFFICE.

HENRY LANGOWSKI, OF CHICAGO, ILLINOIS.

BRAKE-BAND LINING.

Application filed September 22, 1924. Serial No. 739,133.

To all whom it may concern:

Be it known that I, HENRY LANGOWSKI, a citizen of the United States, residing at 2154 N. Oakley, Chicago, in the county of 5 Cook and State of Illinois, have invented new and useful Improvements in Brake-Band Linings, of which the following is a specification.

This invention relates to new and useful 10 improvements in brake-bands and more particularly to the manner in which the lining is applied thereto. The main object of my invention is the provision of a brake-band wherein the lining is applied to the 15 same in such a manner as to entirely cover the rivets or other fastening members and at the same time utilize the entire portion of the lining.

In the usual construction of brake-bands 20 it is customary to secure the lining of the band by inserting the rivet through the lining and then through the metal supporting band, leaving the head of the rivets exposed upon the engaging surface of the lining, 25 whereby only a certain portion of the lining may be used before it is necessary to insert a new one and it is therefore one of the particular objects of my invention to do away with this old method of fastening so as to 30 prolong the life of the brake lining and at the same time secure effective results.

With the above and other objects in view, the invention consists in the novel features 35 of construction, the combination and arrangements of parts hereinafter more fully set forth, pointed out in the claims and shown in the accompanying drawings, in which:

Fig. 1 is a side elevation of the brake lining 40 constructed in accordance with my invention.

Fig. 2 is a plan view.

Fig. 3 is a detailed longitudinal section.

Referring more particularly to the drawings, numeral 1 indicates a metal brake-band 45 which is perforated with spaced openings 2 for receiving the prongs of the securing

rivet 3. These rivets 3 are extended through a facing strip 4 which is preferably formed of leather or a similar material in order to 50 connect the brake lining to the band 1.

A suitable layer of fabric 5 comprises the brake lining and this strip of fabric is attached to the facing strip 4 by means of any suitable type of adhesive as shown at 6 55 and in order to securely retain the fabric 5 in position upon the facing strip 4, rows of stitching 7 are arranged along the edges of the lining and the facing strip, connecting 60 these two parts.

As illustrated in Fig. 3 it will be noted that the head of the rivet 3 is arranged beneath the fabric strip 5 and connects the facing 4 with the band 1. The fabric is then 65 in turn attached to the facing strip 4 and in this position will utilize the entire portion of the fabric lining and at the same time prevent the heads of the rivets 3 from coming in contact with the brake-band.

While I have shown and described the 70 preferred embodiment of my invention, it will be understood that various changes and alterations may be made without departing from the spirit of the invention or the scope of the appended claim:

In combination with a metal brake band having a plurality of spaced openings there thru, a facing strip adapted to lie in abutting relation with the inner face of said band, pronged fastening means carried by 80 the facing strip and adapted to be inserted thru the openings in the brake band and the prongs engaged with the outer surface of the brake band, the heads of said pronged fasteners engaging the inner face of the 85 facing strip, a layer of fabric upon the inner face of the facing strip and covering the heads of the fastening means and a layer of adhesive between the layer of fabric and facing strip whereby to prevent movement 90 of the fabric relative to the facing strip.

In testimony whereof I affix my signature.

HENRY LANGOWSKI.
